UNITED STATES PATENT OFFICE.

FRANK HYDE, OF SIOUX FALLS, SOUTH DAKOTA.

COLLAR-FASTENER.

1,352,268.

Specification of Letters Patent. Patented Sept. 7, 1920.

Application filed February 19, 1920. Serial No. 359,779.

To all whom it may concern:

Be it known that I, FRANK HYDE, a citizen of the United States, residing at Sioux Falls, in the county of Minnehaha and State 5 of South Dakota, have invented certain new and useful Improvements in Collar-Fasteners, of which the following its a specification.

This invention relates to certain new and useful improvements in collar fasteners and the primary object thereof is to provide a fastener which is spring tensioned so as to maintain the collar ends or points under constant tension and still allow same to 5 yield for any reason incident to collar wear.

A further object of the invention is to provide a spring tensioned collar fastener in which the spring is practically concealed and wherein the contractile movement of the 10 two hooks or collar engaging elements is restricted to a predetermined extent.

Still further the invention aims to provide a collar fastener wherein both hooks are tensioned by a single spring and wherein 15 in the structure is simple and economical and possessed of a minimum of parts.

In the drawings:

Figure 1, is a top plan view of the invention;

Fig. 2 is a front elevation;

Fig. 3 is a rear elevation; and

Fig. 4 is an enlarged section on line 4—4 of Fig. 1.

In proceeding in accordance with the 35 present invention a pair of substantially similar members are employed each having a collar engaging hook or pin point 1, formed upon the outer end of a shank 2. The shanks are of substantially rectangular 40 cross-section and having their inner ends turned at right angles at 3 and formed with eyes corresponding to that of the cross-sections of the shanks to slidably receive and prevent rotation of the latter.

Each shank is bent or offset adjacent its

hook or pin point to form a shoulder or stop 4 which engages the adjacent eye member to restrict contractile movement of the members under the influence of the coil spring 5. A single spring is employed which abuts 50 the eye members at its ends and which lies to the rear of the foremost shank, being practically concealed by the latter. Thus the device presents an attractive appearance, and is simple and economical, involving but 55 three parts in its entirety.

It will also be noted that the eyes and hooks present a symmetrical appearance regardless of any position to which the members may be adjusted and that the whole 60 presents an artistic and ornamental appearance which is a commercial requirement to successful sale of articles of this kind.

It will further be noted that the stops 4 are located so as to leave the pin points free 65 for engaging, the collar ends, or in other words are spaced from the pin points so as to not permit the eyes to obstruct or interfere with free engagement of the points with the collar ends.

What is claimed is:—

In a collar fastener, a pair of substantially similar members each having a shank with a pin point on the outer end of the shank, the shanks being of substantially rectangular cross section and having their inner ends turned at right angles and formed with eyes which conformably and slidably receive the shank of the opposite member, and a single coil spring to the rear of one 75 shank and engaged over the other shank and between the eyes, each shank being offset adjacent its pin point to form a stop engaging the eye of the opposite shank to restrict contractile movement of the shanks, the front shank being offset rearwardly and the rear shank being offset forwardly to bring the shanks into alinement.

In testimony whereof I affix my signature.

FRANK HYDE.
